UNITED STATES PATENT OFFICE

JOHN MUELLER, OF CHICAGO, ILLINOIS

HAIR CURLER

Application filed June 11, 1932. Serial No. 616,602.

The present invention relates generally to curlers for women's hair. More particularly, the invention relates to that type of curler which is adapted primarily for use in connection with a permanent wave treatment and is designed to have a lock of hair wrapped therearound and then after the application of a chemically treated wrapper to the hair, to be inserted into one of the heating tubes of a permanent wave apparatus for heat treatment of the hair.

One object of the invention is to provide a curler of this type which is generally an improvement upon, and is more efficient in operation than, previously designed curlers of the same general character, by virtue of the fact that it is constructed to have the lock of hair wrapped flatly therearound and to hold the hair so that all parts thereof are placed under substantially uniform tension.

Another object of the invention is to provide a curler of the type under consideration which comprises a pair of complementary, spindle-like members, one of which is designed to have the inner half of the lock of hair wrapped therearound and the other of which is designed to have the outer half of the lock wrapped therearound and is adapted to be connected to said one member in end-to-end relation.

Another object of the invention is to provide a curler of the last mentioned character in which the member for the inner half of the lock of hair has a shallow recess at one end thereof for receiving the parts of the hair immediately adjacent to the roots, and is provided with a pivotally supported clip which serves when in its operative position, to hold the aforesaid parts of the hair in the recess and conforms to the member as far as peripheral shape is concerned, so that the remainder of the inner half of the lock of hair may be wrapped therearound.

Still another object of the invention is to provide a curler of the character under consideration in which the member for the outer half of the lock of hair embodies a pivotal clip for holding the extreme ends of the hair thereagainst and is adapted to

be rotated so as to wind or wrap the outer half of the lock therearound.

A further object of the invention is to provide a curler of the two-member type in which the member for the outer half of the lock of hair is adapted, after connection in end-to-end relation with the member for the inner half of the lock of hair, to be rotated so as to place the middle, as well as the end parts of the hair, under the proper tension, and embodies simple means whereby it may be locked in place after rotation thereof.

A still further object of the invention is the provision of a clamp device which embodies a comb whereby it may be held in place and serves to hold the inner half of the lock of hair around the one curler-member when the outer half of the lock of hair is being wound or wrapped around the other curler-member.

In addition, it is contemplated as one of the objects of the invention to provide a curler which may be applied readily and expeditiously, consists of but a small number of parts and may be manufactured at a low and reasonable cost.

Other objects of the invention and the various advantages and characteristics of the present curler construction will be apparent from a consideration of the following detailed description.

The invention consists in the several novel features which are hereinafter set forth and are more particularly defined by the claims at the conclusion hereof.

In the drawings which accompany and form a part of this specification or disclosure and in which the preferred embodiment of the invention is shown and like numerals of reference denote corresponding parts throughout the several views:

Figure 1 is a perspective illustrating the manner in which the member for receiving the inner half of the lock of hair is connected by the pivotally supported clip to the parts of the hair immediately adjacent to the roots;

Figure 2 is a perspective showing the curler-member of Figure 1 after the inner

half of the lock of hair is wrapped therearound;

Figure 3 is a perspective exhibiting in detail the manner in which the clamp device 5 is held in place by the comb and serves to hold the inner half of the lock of hair around the member during application of the outer half of the lock of hair to the other curler-member;

10 Figure 4 is a perspective of the other curler-member;

Figure 5 is a perspective showing the manner in which the member of Figure 4 is manipulated or turned so as to wind the 15 outer half of the lock of hair therearound;

Figure 6 is a perspective showing the two curler-members connected together in end-to-end relation and with the lock of hair wrapped therearound;

20 Figure 7 is an end view of the clamp device for retaining or holding in place the member for the inner half of the lock of hair while the outer half of the lock of hair is applied to the other curler-member;

25 Figure 8 is a side view of the curler;

Figure 9 is a transverse section taken on the line 9—9 of Figure 8 and indicating the manner in which the clip on the member for receiving the inner half of the lock of hair 30 is snapped into place; and

Figure 10 is a longitudinal section of the two curler-members.

The curler which forms the subject matter of the present invention is designed primarily for use in connection with a permanent wave treatment and is adapted to have a lock of hair wrapped therearound. It is adapted to be applied manually to the hair and consists of a pair of complementary, 40 spindle-like members 11 and 12 and a clamp device 13.

The curler-member 11 is adapted to have the inner half of the lock of hair wrapped therearound and is formed of aluminum or 45 any other suitable material. It is slightly tapered, as shown in Figures 8 and 10 of the drawings, and embodies a reduced stem 14 at its large end. The small end of the member is cut away to form an elongated, 50 comparatively shallow recess 15. This recess extends lengthwise of the curler-member 11 and is adapted to receive the parts of the hair immediately adjacent to the roots. These parts of the hair are clamped in place 55 within the recess by means of an elongated, substantially semicylindrical clip 16. The latter is formed of sheet metal and embodies at one end thereof a pair of laterally spaced pivot ears 17. A pivot pin 18 in the small 60 end of the curler-member 11 extends through the ears 17 and forms with the latter a pivotal connection whereby the clip 16 is supported so that it may be swung into an operative position alongside of the member 11 65 and over the recess 15. The intermediate

part of the clip 16 is cut away so that when the clip is in its operative position, there is a comparatively small space between the sides of the clip and the recess 15 in order to accommodate and hold flatly the parts of the hair adjacent to the roots. The distal end of the clip is adapted to engage and extend part way around the central part of the curler-member 11 and is so formed that it snaps into place when the clip is swung into its operative position, and thus holds the clip in place. The clip conforms to the circular-member 11 as far as peripheral shape is concerned, and is adapted when in its operative position, to have the part of the inner half of the lock of hair wrapped therearound. In applying the curler-member 11 to the lock of hair, the clip 16 is first swung into its opened position, as indicated by dotted lines in Figure 8. A lock of hair is placed flatly within the shallow recess 15 and the clip is shifted or slid on the hair until it is positioned immediately adjacent to the roots of the hair. After shifting or sliding the curler-member in this manner, the clip 16 is swung into its operative position wherein it serves to clamp the hair within the recess 15 and to hold the curler-member 11 in connected relation with respect to the hair. Upon swinging the clip into place, the inner half of the lock of hair is wrapped around the curler-member, as illustrated in Figure 2.

The clamp device 13 serves to hold the inner half of the lock of hair around the member 11 during winding or wrapping of the outer half of the lock of hair around the member 12, as hereinafter described. It comprises a U-shaped clamp 19 and a comb 20. The clamp 19 is formed from a strip of sheet metal and comprises a pair of oppositely facing, laterally spaced legs 21 and a substantially semi-cylindrical connecting part 22. The outer end parts of the legs 21 are deflected from side to side in order to form substantially semi-cylindrical pockets 23 for receiving the curler-member 11. The extreme outer ends of the clamp legs are bent away from one another so as to facilitate application of the clamp to the curler-member 11. The connecting part 22 is of such character that the legs 21 are urged towards one another and hence hold in place the part of the lock of hair which is wrapped around the member 11. The comb 20 is adapted to be inserted into the hair of the individual to whom the curler is applied and serves to hold in place the U-shaped clamp 19. It is connected to the clamp by a wire 24, one end of which fits within and is soldered or otherwise secured to the semi-cylindrical part 22 of the clamp. The other end of the wire is bent into hook form and extends through and around the central part of the comb, as shown in Fig- 130

ure 7. In applying the clamp device 13 to the curler-member 11, the legs of the U-shaped clamp 19 are sprung around the part of the lock of hair on the curler-member 11 in order to confine such part of the lock within the oppositely facing pockets 23. Thereafter, the comb 20 is inserted into the hair of the individual to whom the curler is applied so that it operates to hold the curler-member 11 in place. The clamp 19 is substantially as wide as the curler-member 11 is long in order that all portions of the lock of hair on the member 11 are clamped in place.

The curler-member 12 is adapted to have wrapped therearound the outer half of the lock of hair and is formed of aluminum or any other suitable material. It has flared ends, as shown in the drawings, and embodies an elongated, sheet metal clip 25. The latter extends longitudinally of the member 12 and is provided at one end thereof with a pair of laterally spaced pivot ears 26. A pivot pin 27 in one end of the curler-member 12 extends through the ears and forms with the latter a pivotal connection whereby the clip may be swung into and out of an operative position against the central part of the member 12. The clip 25 is semi-circular in cross section and corresponds in curvature and design to the periphery of the central or intermediate part of the curler-member 12. The end of the curler-member 12 which has the pivot pin 26 is provided with a knurled head 28 whereby it may be rotated in order to wind or wrap the outer half of the hair therearound. The other end of the curler-member 12 embodies a cylindrical socket 29 for receiving the stem 14 on the large end of the member 11. In applying the curler-member 12 to the other half of the lock of hair, the clip 25 is swung into its opened position and the extreme outer ends of the hair are placed against the central part of the member 12. Thereafter, the clip 25 is swung into its operative position in order to clamp the hair ends to the member 12. After clamping of the hair ends, the member 12 is turned by manipulation of the knurled head 28 so as to wrap the outer half of the lock of hair around the member 12. After the outer end of the lock of hair is wrapped completely around the member 12, the member is positioned axially with respect to the curler-member 11 and is manipulated or shifted so as to effect insertion of the stem 14 in the socket 29. In this position of the stem, the two curler-members are connected in end-to-end relation and so that the member 12 may be rotated relatively to the member 11 in order to place the central part of the strand of hair under the desired tension. For the purpose of locking the curler-member 12 to the member 11, a bolt 30 is provided. The shank of

this bolt extends through a longitudinal bore 31 in the central part of the member 12 and embodies an externally threaded end part which is designed to fit within an internally threaded socket in the stem 14. The head of the bolt abuts against the knurled head 28 and is adapted to be rotated when it is desired to lock the two curler-members together. The bolt 30 constitutes simple means for locking the curler-member 12 to the member 11 after the former is rotated to the desired extent or degree in order to place the lock of hair under the desired tension.

The curler is applied by first wrapping the inner half of the lock of hair around the member 11. This is done in the manner previously indicated and after the member 11 has been connected to the root parts of the hair by the clip 16. During winding of the outer half of the lock of hair on the curler-member 12, the clamp 19 of the clamp device 13 is snapped over the end into place on the member 11. After such clamping of the hair, the comb 20 is embedded into the hair at the proper point so as to hold the member 12 in the proper position. While the curler-member 11 is held in place by the clamp device 13, the outer half of the lock of hair is wrapped or wound around the member 12. This is accomplished as previously pointed out, by clamping the ends of the hair against the central portions of the member 12 and then turning or rotating the member 12 by means of the knurled head 28. After the outer half of the lock of hair is wound or wrapped in place, the curler-member 12 is connected in end-to-end relation with the member 11 by shifting the reduced stem 14 into the socket 29. In this position, the curler-member 12 is rotated relatively to the member 11 until all parts of the lock of hair are placed under the desired or proper tension. After rotation of the member 12 to the desired extent, the bolt 29 is turned in order to lock the two curler-members together and hold them against relative rotation. Thereafter, the clamp device is removed and a chemically treated wrapper is applied to the hair. With this wrapper in place, the curler is placed within one of the heating tubes of a permanent wave apparatus for heat treatment of the hair, as well understood in the art.

The herein described curler is exceedingly simple, as far as construction is concerned, and hence may be manufactured at a low and reasonable cost. It is exceedingly efficient in operation in that it is so designed that the lock of hair is wrapped in a flat manner and has all parts thereof placed under the same degree of tension.

The invention is not to be understood as restricted to the details set forth, since these may be modified within the scope of

the appended claims, without departing from the spirit and scope of the invention.

Having thus described the invention, what I claim as new and desire to secure 5 by Letters Patent, is:

1. In a curler of the character described, the combination of a spindle-like member adapted to have the inner half of a lock of hair wrapped therearound, a second spindle-like member adapted to have the outer half of the lock of hair wrapped therearound, and means for connecting the two members in end-to-end relation. 10
2. In a curler of the character described, the combination of a spindle-like member adapted to have the inner half of a lock of hair wrapped therearound, a second spindle-like member adapted to have the outer half of the lock of hair wrapped therearound, and means for connecting the members in end-to-end relation and so that the second member may be rotated relatively to the first mentioned member in order to effect a tight wrapping of the intermediate part of the lock of hair around the members and place the hair under the desired tension. 15
3. In a curler of the character described, the combination of a spindle-like member adapted to have the inner half of a lock of hair wrapped therearound, a second spindle-like member adapted to have the outer half of the lock of hair wrapped therearound, means for connecting the members in end-to-end relation and so that the second member may be rotated relatively to the first mentioned member in order to effect a tight wrapping of the intermediate part of the lock of hair around the members and place the hair under the desired tension, and releasable means whereby the second member may be locked in place after it has been rotated to the desired extent. 20
4. In a curler of the character described, the combination of a spindle-like member adapted to have the inner half of a lock of hair wrapped therearound, a second spindle-like member provided with means whereby it may be attached to the ends of the hair and adapted to be turned in order to wrap the outer half of the lock of hair therearound and then to be placed in end-to-end relation with respect to the first mentioned member, and a stem and socket connection 25 between the contiguous ends of the two members operative to permit the second member to be rotated relatively to said first mentioned member in order to effect a tight wrapping of the intermediate part of the hair around the two members and place the hair under the desired tension. 30

5. In a curler of the character described, the combination of a spindle-like member adapted to have the inner half of a lock of hair wrapped therearound and provided at 35

one end thereof with a reduced stem, and a second spindle-like member provided with means whereby it may be attached to the ends of the hair and adapted to be turned in order to wrap the outer half of the lock of hair therearound and then to be placed opposite the stem and in end-to-end relation with respect to the first mentioned member, said second member having a socket in the end thereof contiguous to the stem for receiving the stem and forming a connection whereby said second member may be rotated relatively to the first mentioned member in order to effect a tight wrapping of the intermediate part of the hair around the two members and place the hair under the desired tension. 70

6. In a curler of the character described, the combination of a spindle-like member adapted to have the inner half of a lock of hair wrapped therearound, a second spindle-like member adapted to have the outer half of a lock of hair wrapped therearound, means for connecting the members in end-to-end relation and so that the second member may be rotated relatively to the first mentioned member in order to effect a tight wrapping of the intermediate part of the lock of hair around the members and place the hair under the desired tension, and a bolt extending longitudinally through said second member and arranged to be inserted into a threaded socket in the contiguous end of the first mentioned member in order to form a clamping instrumentality whereby the two members may be clamped together after the said second member has been rotated to the desired extent. 80

7. In a curler of the character described, the combination of a spindle-like member adapted to have the inner half of a lock of hair wrapped therearound and provided at one end thereof with a reduced stem, a second spindle-like member provided with means whereby it may be attached to the ends of the hair and adapted to be turned in order to wrap the outer half of the lock of hair therearound and then to be placed opposite the stem and in end-to-end relation with respect to the first mentioned member, said second member having a socket in the end thereof contiguous to the stem for receiving the stem and forming a connection whereby said second member may be rotated relatively to the first mentioned member in order to effect a tight wrapping of the intermediate part of the hair around the two members and place the hair under the desired tension, and a bolt extending longitudinally through the second member and arranged to be inserted into an internally threaded socket in the stem of the first mentioned member in order to form a clamping instrumentality whereby the two members may be locked together after the second 90

- member has been rotated to the desired extent.
8. In a curler of the character described, the combination of a spindle-like member adapted to have the inner half of a lock of hair wrapped therearound, a second spindle-like member adapted first to have the ends of the lock of hair placed thereagainst, then to be rotated in order to wind the outer half of the lock of hair therearound, and finally to be positioned in end-to-end relation with respect to the first mentioned member, and a bolt extending longitudinally through one of the members and arranged so that the shank thereof may be inserted into an internally threaded socket in the contiguous end of the other member in order to form a clamping instrumentality whereby the two members may be locked together.
9. In a curler of the character described, the combination of a spindle-like member provided with a clip whereby it may be attached to a lock of hair near the roots of the hair, said member and clip being shaped to have the inner half of the lock of hair wrapped therearound, a second spindle-like member adapted to have the outer half of the lock of hair wrapped therearound, and means for connecting the two members in end-to-end relation.
10. In a curler of the character described, the combination of a spindle-like member having a longitudinally extending, comparatively shallow recess at one end thereof for receiving a lock of hair near the roots of the hair, said member having a clip for clamping the hair in the recess and being adapted to have the inner half of the lock of hair wrapped therearound, a second spindle-like member adapted to have the outer half of the lock of hair wrapped therearound, and means for connecting the two members in end-to-end relation.
11. As a new article of manufacture, a spindle-like curler-member having a longitudinally extending, comparatively shallow recess at one end thereof for receiving a lock of hair, and an elongated clip connected pivotally to the said one end of the member so that it may be swung into an operative position wherein it extends alongside of the member and clamps the hair within the recess, the outer or distal end of said clip being provided with means for engaging frictionally the sides of the member and holding the clip in its operative position.
12. In a curler of the character described, the combination of a spindle-like member adapted to have the inner half of a lock of hair wrapped therearound, a second spindle-like member provided with a clip whereby it may be attached to the outer ends of the hair, said second member being adapted to be turned in order to wind the outer half of the lock of hair therearound and then to be positioned in end-to-end relation with respect to the first mentioned member, and means for connecting the two members together after the second member has been shifted into the aforesaid end-to-end relation.
13. In a curler of the character described, the combination of a spindle-like member adapted to have the inner half of a lock of hair wrapped therearound, a second spindle-like member having a clip pivotally connected to one end thereof for clamping the outer ends of the hair against the second member, said second member being adapted to be rotated in order to wind the outer half of the hair therearound and then to be positioned in end-to-end relation with respect to the first mentioned member, and means for connecting the two members together after the said second member is positioned as aforesaid.
14. In a curler of the character described, the combination of a spindle-like member adapted to have the inner half of a lock of hair wrapped therearound, a second spindle-like member adapted to have the outer half of the lock of hair wrapped therearound, means for connecting the two members together in end-to-end relation, and a spring clamp for holding the inner half of the lock of hair around the first mentioned member during wrapping of the outer half of the lock of hair around the second member.
15. In a curler of the character described, the combination of a spindle-like member adapted to have the inner half of a lock of hair wrapped therearound, a second spindle-like member adapted to have the outer half of the lock of hair wrapped therearound, means for connecting the two members together in end-to-end relation, clamp-means for holding the inner half of the lock of hair around the first mentioned member during application of the outer half of the lock of hair to the second member, and a comb attached to said clamp-means and adapted to be embedded in the hair of the individual to whom the curler is applied in order to hold in place said clamp-means with the first mentioned member.
- Signed at Chicago, Illinois, this 8th day of June, 1932.
- JOHN MUELLER.
